UNITED STATES PATENT OFFICE.

EARNEST JOSEPH ALLISON, OF WHITEFISH, MONTANA.

SWITCH.

1,287,568.

Specification of Letters Patent. Patented Dec. 10, 1918.

Application filed April 18, 1918. Serial No. 229,436.

To all whom it may concern:

Be it known that I, EARNEST J. ALLISON, a citizen of the United States, and a resident of Whitefish, in the county of Flathead and State of Montana, have invented certain new and useful Improvements in Switches, of which the following is a specification.

My invention is an improvement in switches, and has for its object to provide a switch which may be automatically operated by train carried means for opening or closing the switch at all times when a train passes in either direction on the main or side tracks.

15 A further object is to provide a switch including means for opening the same when a train is to go into the siding, means for automatically latching the switch in open position, and means for automatically tripping the latching means after the train is in the siding.

In the drawings:—

Figure 1 is a diagrammatic plan view of a switch constructed in accordance with the 25 invention.

Fig. 2 is a section on the line 2—2 of Fig. 1, looking in the direction of the arrows adjacent the line.

Fig. 3 is a detail transverse vertical section corresponding to the right hand portion of Fig. 2, showing the way in which the switch lever is actuated by the train carried shoe.

Fig. 4 is an enlarged bottom plan view of 35 the said shoe.

Fig. 5 is a detail plan view of the switch point operating mechanism.

Fig. 6 is a partial bottom plan view of the same.

40 Fig. 7 is a section on the line 7—7 of Fig. 5, looking in the direction of the arrows adjacent the line.

Figs. 8, 9, and 10 are sections all taken on the line 8—8 of Fig. 5, showing the 45 switch mechanism in various positions during its operation.

In the present embodiment of the invention, 5 indicates the main line track rail, 6 the cross ties, and 7 the switch points, the 50 numeral 8 being applied to the rails of the side track.

At a point about an engine's length from the switch points on the main and side tracks is a switch lever 9 pivoted intermediate its ends to a bracket 10 supported by

the rail, and the upper end of the lever 9 is provided with arms 11 which curve away from the rails, in such manner that a train carried shoe 12 when dropped upon the rails, as a train approaches, may engage the 60 upper ends of the levers for swinging the same away from the rails.

A pair of shoes may be carried by the locomotive and a pair by the caboose or rear car of the train, so that a shoe may be 65 dropped upon either of the rails of the track at the front or at the rear end of the train as may be desired.

Each shoe consists of a flat portion or plate adapted to travel along the tread of 70 the rail and a depending double wedge shaped flange 14 adapted to travel along the outer edge of the tread, the flange being adapted to act as a wedge to slide between the arms 11 and the rails to engage the 75 switch lever in order to throw the same.

A lug 13 is provided at the center of the plate portion of the shoe, and this lug is pivoted between the arms of the fork at the lower end of mechanism operable from the 80 train for raising and lowering the shoe. Each switch lever is normally held in contact with the adjacent rail by means of a spring 15 connected at one end to the lever below its pivot connection, and connected 85 at its other end to an adjacent cross tie or other fixed object.

Rods 17 are arranged transversely of the main track between the cross ties and beneath the rails, and each is pivotally connected at one end to the lower end of a switch lever 9 and connected at the opposite end to a lug 19 depending from one arm of a bell crank lever 20 pivoted at 21 to the top of the tie. The other arm of each lever is pivotally connected to one end of a reach rod or link 22 which extends longitudinally 95 of the track adjacent one rail and on the opposite side of the track from the switch lever 9.

100 For the sake of clearness, the switch lever at the left of Fig. 1 will be hereafter termed the lever A, that at the right on the siding lever B, and that on the right in the main line C, and the switch levers indicated at B and C are both connected to the adjacent rod 17, the said rod being of a length to extend from the left hand main line rail in Fig. 1 to the left hand siding line rail, and it will be evident that either the lever B or 110

that at C will operate the rod 17 and the reach rod 22 adjacent to the rod 17. Both the reach rod 22 extending from the lever A and that extending from the switch levers 5 B and C extend toward the switch points 7.

The switch points 7 are pivoted as indicated at 24 to a shifting bar 25 arranged between adjacent cross ties 6 and this shifting bar is mounted to slide on substantially U-shaped bridges 26 secured between the

10 U-shaped bridges 26 secured between the cross ties, the shifting bar being arranged between the bridges and the base flanges 27 of the rail. This shifting bar when moved longitudinally transversely of the track will
15 carry with it the switch points 7 so that the switch will be opened or closed, depending upon the direction of movement of the switch bar.

As shown in Fig. 5, the reach rods or links 22 are connected at the ends adjacent to the switch points to block actuating bell crank levers 28, the said levers 28 being pivoted to plates 29 secured to ties at opposite sides of the shift bar and at the outer sides of the rail. These levers as will be evident from inspection of Fig. 5 are oppositely arranged. Each end of the shift bar 25 carries a housing 28^a extending longitudinally thereof, each housing being open at one end and the open ends extending in the same direction. Each housing has a base portion 30 riveted to the shift bar to secure the housing in place, and the housings are so arranged that their open ends extend toward the sides of the main track on which is the side track.

Blocks 31 are mounted to slide in the housings upon the shift bar and independently of the movement thereof, and they are guided in their movement by the housings, 40 the upper surfaces of the blocks 31 being spaced from the tops or roofs of the housings. The block levers have the inner arms remote from the links or reach rods 22 extending through slots or openings 32 in the 45 sides of the housings and in the recesses 33 in the blocks 31. Each of the said arms of the levers 28 has a slot which engages a stud 34 on the block, and it will be evident that when the levers 28 are swing the blocks will 50 be moved longitudinally of the housings.

50 be moved longitudinally by the following. Latch carrying levers 35 extend through the slots in the shift bar at each end thereof, the said levers being pivoted to brackets 36 depending from the shift bar and each lever 55 carries at its upper end a latch 37, each latch being pivoted to the lever. The lower ends of the levers are connected by a link 38, and this link is pivotally connected near one end to one of the arms of a bell crank 60 lever 39 pivoted to a bracket 40 on the underside of the shift bar. The other arm of the bell crank has an upwardly extending finger 41 which is adapted to pass through a slot in the shift bar, and a coil spring 42 acts 65 normally to force the finger through the

opening in the bar. This spring is arranged on a rod 43 which depends from the shift bar and passes through an opening in the arm of the elbow lever, the spring encircling the rod between the lever and a stop adjustable on the rod. This lever 39 is a trip lever and the lever is normally held in the locking position of Fig. 9, *i. e.*, through the opening in the shift bar by the spring. 75

The finger 41 is so placed that when the main track is open, as shown in Fig. 8, the finger will be beneath the base flange of the adjacent rail 5 and will be held in contact therewith by the spring 42. The switch 80 points are normally held in the position shown in Fig. 8 *i. e.*, with the side track closed by means of a heavy coil spring 44 which is arranged between a rail 5 and a stop 45 adjustable on the rod 46 rigidly connected 85 with a switch point 7, and extending through an opening in the main line rail 5. The spring is between the stop and the main line rail, and acts to draw the switch points into closed position. This spring 44 is arranged 90 at the opposite side of the track from the bell crank 39 and adjacent to the inner main line rail or that rail which is closest to the side track.

The latches 37 have catches or hooks at 95 one end, and these catches or hooks are adapted to engage recesses 46 in the blocks 31 before mentioned. These latches 37 extend into the housings 28^a to engage the blocks, and it will be noticed that each latch 100 has an upwardly curved tail 47 which when the latches are in engagement with the blocks, extend slightly above the tops of the housings. When the shift bar 25 is moved, the housings 28^a, the latches 37, and 105 latch carrying levers 35, the link 38, the trip lever 39, and switch points 7 move therewith, while the blocks 31 are movable independently of the shift bar, and are actuated by means of the switch levers 9 above mentioned.

If for instance, a train is coming from the left of Fig. 1, and the side track is set to the main line the shoe on the left hand side of the locomotive will be dropped to the left hand main rail 5, as indicated in Fig. 1. The parts are shown in Fig. 8 in the same position as they are shown in Fig. 1, *i. e.*, with the switch set for the main line, and each Fig. 8, 9, and 10 is looking in the same direction in which the train is moving.

The blocks 31 in Fig. 8 are near the closed ends of the housings. As the shoe moves into engagement with the lever 9 in position A, the block 31 which is on the right hand side of Fig. 8 will be moved toward the left through the medium of the rods and bell crank levers connecting the block with the lever at position A and the block will engage the wall of the housing to move the shift 130

bar. Thus the shift bar 25 will be moved toward the left against the tension of spring 44.

The block at the left of Fig. 8 will remain stationary and as the switch point 7 at the left comes in contact with the adjacent rail 5, the shift bar will remove sufficiently to move the finger 41 to clear the rail 5 and extend upward into the position shown in Fig. 9. The pull on the switch points of the spring 44 is now counter-acted to some extent by the engagement of this finger 41 with the rail 5 and the switch points are thus held in the position shown.

During the movement of the trip lever 39 in the position shown in Fig. 9, the link 38 will be shifted to the left, thus swinging the latch levers 35 connected therewith, the latches through gravity engaging with the notches or recesses 46 of the blocks. It will be evident that when the latches are in the position of Fig. 8 the tails 47 of the latches by their engagement with the housings 28^a are held out of engagement with the blocks. When the latches are tripped, the bar will have been shifted far enough so that the hook of the left hand latch will be in position to drop into the recess in the block at the left of the figure. This movement of the parts will take place during the short interval of time which the shoe 12 consumes in passing the lever 9 at the position A. Immediately the shoe passes out of engagement with the lever, the spring 15 connected with the said lever will throw the upper end of the same back into engagement with the rail, thus shifting the block at the right toward the open end of the housing and in the position shown in Fig. 9. The block will now be forced against the adjacent latch 37 raising the same sufficiently, so that the hook may engage in the recess in the block.

It will be evident therefore that as a train approaches the side track, the lever at position A will be shifted to throw the switch, and will subsequently be brought back to normal position by reason of its spring 15, the block at the right of Figs. 8, 9, and 10 meanwhile remaining stationary and this movement of the switch points and subsequent movement of the lever at position A into normal position, will position the parts so that the switch is locked by means of the trip lever, and the latches 37 are in engagement with the respective blocks.

Upon the passage of the shoe carried by the locomotive beyond the lever at position A, said shoe will be lifted, and the train will pass onto the side track, and the left hand shoe carried by the caboose or rear car of the train, as said rear car moves onto the side track beyond the switch points may be dropped into position to actuate the lever at position B.

As the said lever is actuated its cross rod 17 will be drawn to the left or toward the top of Fig. 1, thus shifting the block at the left of Fig. 9 to the left, the block at the right meanwhile remaining stationary. As the block at the left moves toward the left, through the medium of this adjacent latch 37, the latch levers 35 will be shifted, the shift bar remaining stationary because of the engagement of the left hand switch point with the adjacent main track rail, and the link 38 will be shifted toward the right thus drawing the finger 41 downwardly and moving the levers until the upturned portions of the latches are about to engage the tops of the housings, at which point the finger will be almost below the level of the rail.

This position is shown in Fig. 10, and it is evident that as the block at the left moves farther toward the left, as the shoe moves farther into engagement with the switch lever B, the adjacent latch 37 by engagement with the top of the housing will be tripped out of engagement with the block at the left, whereupon the spring 44 will immediately shift the switch points into the position shown in Fig. 8, the parts in the meantime having moved so that the finger 41 is just below the base flange of the rail. As the latch levers 35 on the left are moved by the action of the block at the left, the latch lever on the right is similarly turned, so that when the left hand latch is out of engagement with the left hand block, the right hand latch will be out of engagement with the right hand block, and when the shift bar moves to the right the right hand latch will not engage the right hand block, but will be in the position shown in Fig. 8.

It is evident from the above, that a train passing in the direction indicated will first operate the lever, at position A to automatically open the switch, and after passing into the side track, will operate the lever at position B to trip the mechanism through the medium of the left hand block so that the switch will be automatically closed. Should the train pass on the main track, from the right of Fig. 1, the switch points being in the position such that the siding is open, one of the shoes of the engine may be dropped to engage the lever at position C, whereby the switch may be tripped to permit the train to pass, and should the train be approaching from the right at Fig. 1 on the siding, the switch points being closed, one of the shoes may be dropped to operate the lever at position B, to throw the switch so that the train might pass from the siding on the main track. In either case, should it be desired to re-open the switch, so that it will remain open after the train has passed one of the shoes at the rear of the train may be dropped to operate the lever at position A.

By the construction shown and described it will be evident that either of the blocks may be operated for opening the switch, and that either may be operated for tripping the switch to permit the same to close. While the switch has been described as being automatically operable by train carried shoes, it may equally well be operated by means of a hand lever.

10. I claim:

1. A switch mechanism including main line rails, side track rails and movable switch points for controlling the entrance of trains onto the side track rails, a shift bar 15 to which said switch points are secured, a switch lever positioned on the main rail at a distance from said shift bar, a cross rod connected to said lever, a bell crank lever to which said cross rod is pivoted, a reach 20 rod to which said bell crank lever is pivoted, a switch lever positioned on one of the siding rails, a cross rod connected to second said switch lever, and extending across the main rails, a third switch lever connected to one 25 of the main rails, said third switch lever being connected to said second cross rod, a second bell crank lever to which said second cross rod is pivoted, a second reach rod to which said second bell crank lever is pivoted, 30 said reach rods extending toward said shift bar, and means associated with said reach rods and shift bar for moving the latter in one direction when one of the said switch levers is moved, means for locking said shift bar when moving into one position, and means associated with said shift bar and reach rods for tripping said locking mechanism when one of said levers is subsequently operated.

40. 2. A switch mechanism including main rails and switch points, a shift bar positioned transversely of said main rails, and connected to said switch points, spring means for normally holding said switch points in one position, housings carried by said shift bar, blocks movable independently of each other and of said shift bar and supported on said bar within said housings, latch levers supported by said bar, a link connecting said 45 latch levers, latches pivoted to said levers, a trip lever supported by said shift bar and connected to said link, a finger carried by said trip lever adapted to engage one of the main rails when said bar is shifted out of 50 normal position, spring means for normally holding said trip lever in position whereby said finger may engage said rails, means operable at a distance for moving said blocks in a position to shift said bar, said blocks 55 when said bar is in shifted position, adapted to be engaged by the said latches in position to trip said trip lever, and means operable at a distance for moving said blocks whereby to trip said trip lever.

65. 3. A switch mechanism including main

rails, and switch points, a shift bar to which said switch points are connected, housings carried by said shift bar, blocks movable independently of said shift bar and supported thereon within said housings, means for normally holding said shift bar in one position, a trip lever carried by said shift bar, means for normally holding said lever whereby to lock said bar relatively to said main rails when said bar is shifted, means 70 operable at a distance for moving one of said blocks into engagement with one of said housings whereby to shift said bar, means associated with said trip lever and blocks whereby when one of the latter is shifted 75 subsequently to the shifting of said bar, said trip lever may be tripped, and means operable at a distance for moving one of said blocks subsequently to the shifting of said bar.

4. A switch mechanism including main rails and switch points, a shift bar to which said points are connected, means for normally holding said shift bar in one position, a housing carried by said shift bar, a block 90 carried by said shift bar within said housing and movable independently of said shift bar, a trip lever carried by said shift bar adapted to engage one of said rails when said bar is shifted for locking the bar in shifted position, a latch lever pivotally carried by said shift bar, a link connecting said trip and latch levers, a latch carried by said latch lever and normally engaged against said housing in raised position, said latch adapted to be engaged by said block subsequently to the shifting of said bar, and means operable at a distance for moving said block, said block upon initial movement being adapted 95 to shift said bar and upon subsequent movement to actuate said trip lever.

5. A switch mechanism including a switch bar, a housing secured thereon, a block movable within said housing independently of said shift bar, a bell crank lever, said housing provided with a slot through which one arm of said lever extends, said block provided with a recess into which said lever arm extends, said lever arm provided with an elongated slot, a pin extending through the 100 slot of said lever arm for connecting said arm to said block and means for operating said block lever.

6. A switch mechanism including a shift bar, switch points carried thereby and movable therewith, trip means associated with said shift bar for holding the latter in shifted position, said means including a latch lever, means for pivotally supporting said lever on said shift bar, a housing carried by 110 said shift bar, said lever at one end extending into said housing, a latch pivoted to said lever and having a portion adapted to engage said housing when said lever is in 115 position, for holding said latch in raised 120 position.

position, a movable block for operating said shift bar, coacting means between said latch and block for locking them subsequently to the shifting of said bar, and means for operating said block.

7. A switch mechanism including a shift bar, movable switch points connected to said shift bar and movable therewith, a block movable independently of said bar, means carried by said bar adapted to be engaged by said block when the latter is moved in one direction for shifting said bar, means connected with said bar for locking the same when in shifted position, and means operable by said block for tripping said locking means when said block is moved subsequently to the shifting of said bar.

8. A switch mechanism including main rails, and switch points, a shift bar to which

said points are connected, means for normally holding said bar in one position, an element movable independently of said shift bar, and adapted when moved in one position to shift said bar out of normal position, means for normally holding said element in one position, whereby to return said element to normal position subsequently to the shifting of said bar, locking mechanism associated with said shift bar and adapted to lock the latter in shifted position, and means operable by said element for tripping said locking means when said element is moved subsequently to the shifting of said bar.

EARNEST JOSEPH ALLISON.
